UNITED STATES PATENT OFFICE

157,125

COSMETIC CONTAINER OR SIMILAR ARTICLE

Frederick M. Breen, White Plains, N. Y., assignor to Coty, Inc., Wilmington, Del., a corporation of Delaware

Application March 26, 1948, Serial No. 145,368

Term of patent 14 years

(Cl. D86—10)

To all whom it may concern:

Be it known that I, Frederick M. Breen, a citizen of the United States, residing at White Plains, in the county of Westchester and State of New York, have invented a new, original, and ornamental Design for a Cosmetic Container or Similar Article, of which the following is a specification, reference being had to the accompanying drawing, forming part thereof.

In the drawing:

Fig. 1 is a top perspective view of a cosmetic container or similar article, showing my new design;

Fig. 2 is a side elevational view thereof.

Fig. 3 is a view similar to Fig. 2 but turned 90 degrees.

Fig. 4 is a top plan view.

I claim:

The ornamental design for a cosmetic container or similar article, as shown.

FREDERICK M. BREEN.
